UNITED STATES PATENT OFFICE.

WILLIAM GENTRY SHELTON, OF NEW YORK, N. Y.

MEANS FOR FASTENING VIBRATORS TO HANDS OF MASSEURS.

Application filed July 13, 1923. Serial No. 651,297.

To all whom it may concern:

Be it known that I, WILLIAM GENTRY SHELTON, a citizen of the United States of America, residing in the borough of Manhattan, city and State of New York, have invented certain new and useful Improvements in Means for Fastening Vibrators to Hands of Masseurs, of which the following is a specification.

10 This invention relates to devices for producing vibrations of masseurs' hands, and provides improvements in the means for fastening these vibrators to the hands of the users.

15 Heretofore straps of rubber, leather or fabric have been used for attaching or binding vibrators of the character in question to the hands of users,—mostly masseurs and barbers. Lately health authorities in New

20 York city have prohibited the use of such vibrators because straps of the kind mentioned are held to be unsanitary.

It has been proposed to substitute clamping devices for the prohibited straps, but 25 these are not satisfactory, owing to the discomfort to the hands of the users, to the constrictions upon users in the manipulation of their hands, and to the hurts administered to customers undergoing massage by parts 30 of the clamp striking a bony part of their anatomy.

As the result of considerable experimentation applicant has produced a fastening means functioning very similarly to the 35 straps heretofore in use, which is regarded by the health authorities as complying with sanitary requirements, and the parts of which that come into contact with the skin of customers and the hand of the user may be 40 sterilized by heat without damaging said parts.

An embodiment of said invention is illustrated in the accompanying drawings, in which

45 Figure 1 is a perspective view showing the vibrator fastened to the hand of a masseur.

Fig. 2 is a front view of the attaching means, together with the head of the vibrator.

50 Fig. 3 is a side view of the parts shown in Fig. 2.

Fig. 4 is a detail view.

Referring to said drawings, numeral 10 designates a part of a vibrator adapted to 55 bear against the back of a hand, and is conveniently a plate formed integrally with the

casing or head 12 of the vibrator, as shown in the drawings. The vibrator may have the form of a weight 14, mounted eccentrically in the casing 12, and driven by a flexible 60 shaft 16.

Straps 20, 21 are provided for fastening the plate 10 against the back of the hand. These straps 20, 21 are preferably in the form of flat strips of metal or like material, 65 attached in suitable manner to a part of the vibrator, as the plate 10.

Resilient means are provided permitting of the hand being inserted between said straps 20, 21 and the back of said plate 10. 70 These means are preferably springs 26 between the straps 20, 21 and the plate 10, these springs being preferably coil-springs which pass over the back of the plate 10 and are held in place thereon by straps or guides 75 28. These guides 28 are conveniently metal strips having hooked ends 29 adapted to project through a slot 30 in the plate 10, and engage the underside thereof, as shown most clearly in Fig. 4. The straps or guides 28 may 80 be easily removed or replaced by squeezing the ends 29 toward one another, and lifting into and out of place, thereby providing a ready means for releasing the straps 20, 21 for removal and replacement. The removed straps 85 20, 21 may be thus conveniently sterilized.

The straps 20, 21 are upturned at their ends, as indicated at 33, and preferably have ears 35 pivotally connected thereto in a manner to permit the straps 20, 21 to swing on an 90 axis longitudinally thereof, as indicated at 37, which facilitates the adjustment of the straps to the hand. The ears 35 are preferably formed with a recess 39 adapted to receive a pin 40, and the ends of the coil 95 springs 26 are conveniently attached to the pins 40 through slots 42 in said ears.

The underside of the plate 10 is preferably cushioned for comfort. These cushions are preferably sponge rubber blocks 50, 51, and coact with the springs 26 to hold the plate snugly against the back of the hand. These rubber cushions may in fact constitute the sole resilient means by which the straps 50, 51 are caused to firmly or snugly fasten 100 the plate 10 to the hand. These rubber cushions 50, 51 are conveniently fastened to the plate 10 by means of wire loops 53 passing through the cushions, and through the plate, and having the ends thereof bent over 110 into the plate, as indicated at 55, Fig. 4.

The straps 20, 21 which act to hold the

plate 10 on which the vibrator is carried, snugly and firmly against the back of the user's hand, lie flat across the palm of the hand and in such positions as not ordinarily 5 to come into contact with the body or face of a person being massaged, and if these straps do come into contact with the body or face of a person undergoing treatment, they do not cause injury or annoyance.

10 Moreover, the straps are of a nature and construction not to readily receive and harbor germs, and are readily removable for and susceptible to sterilization by means of heat, or other means of sterilization. Instead 15 of metal, strips of other material, as of celluloid, hard rubber, bakelite and other horn-like substances, may be used for the strips 20, 21, and these substances are considered as within the scope of equivalents 20 for the metal, which is preferred, and recited in the claims.

The invention may receive other forms of embodiment than that herein specifically illustrated and described.

25 What is claimed is:

1. Means for fastening vibrators to the hands of masseurs comprising a part of the vibrator adapted to bear against the back of the hand, and straps for fastening said 30 part in place, said straps comprising strips of metal adapted to cross the face of the hand, and a spring attached to the ends of said strap adapted to draw said strap toward said vibrator and against the hand when between said vibrator part and strap, and ears pivoted to the ends of said straps, and permitting swinging movement of said strap, said spring being connected to said strap through said ears and being a coil spring adapted to cross the back of said 35 vibrator part, and means for detachably connecting said strap to said vibrator part, whereby it may be removed for sterilization.
2. Means for fastening vibrators to the hands of masseurs comprising a part of the vibrator adapted to bear against the back of the hand, and straps for fastening said part in place, said straps comprising strips 40

of metal adapted to cross the face of the hand, and a spring attached to the ends of said strap adapted to draw said strap toward said vibrator and against the hand when between said vibrator part and strap, said spring being a coil spring adapted to cross the back of said vibrator part, and means for detachably connecting said strap to said vibrator part, whereby it may be removed for sterilization. 45

3. Means for fastening vibrators to the hands of masseurs comprising a part of the vibrator adapted to bear against the back of the hand, and straps for fastening said part in place, said straps comprising strips of metal adapted to cross the face of the hand, and a spring attached to the ends of said strap adapted to draw said strap toward said vibrator and against the hand when between said vibrator part and strap, ears pivoted to the ends of said straps, and permitting swinging movement of said strap, said spring being connected to said strap through said ears and being a coil spring adapted to cross the back of said 50 vibrator part, and means for detachably connecting said strap to said vibrator part, whereby it may be removed for sterilization. 55

4. Means for fastening vibrators to the hands of masseurs comprising a part of the vibrator adapted to bear against the back of the hand, and straps for fastening said part in place, said straps comprising strips of metal adapted to cross the face of the hand, a spring attached to the ends of said strap adapted to draw said strap toward said vibrator and against the hand when between said vibrator part and strap, and means for detachably connecting said strap to said vibrator part, whereby it may be removed for sterilization. 60

In witness whereof, I have hereunto signed my name.

WILLIAM GENTRY SHELTON.
